UNITED STATES PATENT OFFICE.

JAMES E. LYNCH AND ARTHUR R. SANDT, OF MINNEAPOLIS, MINNESOTA, ASSIGNEES
TO PAGE & HILL COMPANY, OF MINNEAPOLIS, MINNESOTA, A CORPORATION OF
MINNESOTA.

POLE-PUNCTURING MACHINE.

Application filed August 29, 1921. Serial No. 496,651.

To all whom it may concern:

Be it known that we, JAMES E. LYNCH and ARTHUR R. SANDT, citizens of the United States, residing at Minneapolis in the county 5 of Hennepin and State of Minnesota, have invented certain new and useful Improvements in Pole-Puncturing Machines; and we do hereby declare the following to be a full, clear, and exact description of the invention, 10 such as will enable others skilled in the art to which it appertains to make and use the same.

Our invention has for its object to provide a highly efficient machine for producing surface punctures or indentations in wooden poles, thereby adapting the same, at the punctured areas, to absorb creosote, or other wood preserving material, to a very considerable depth.

Generally stated, the invention consists of the novel devices and combinations of devices hereinafter described and defined in the claims.

This improved puncturing machine is 25 adapted for use in puncturing various different kinds and sizes of wooden poles or posts, but has been especially designed and particularly adapted for use in puncturing large and long wooden poles, such as telegraph poles.

It is a fact demonstrated by experience, that wooden poles or posts, set into the ground, are subject to the most rapid decay at the surface of the ground and for a short 35 distance below and above the ground. This improved machine has, therefore, been especially designed to perforate telegraph poles and the like around such areas, but of course, may be readily adapted to apply the punctures wherever they may be desired.

A commercial form of the puncturing machine or apparatus is illustrated in the accompanying drawings, wherein like characters indicate like parts throughout the 45 several views.

Referring to the drawings:

Fig. 1 is a side elevation illustrating the complete machine, some parts being broken away;

Fig. 2 is a horizontal section taken approximately on the line 2—2 of Fig. 1, some parts being broken away;

Fig. 3 is an enlarged transverse vertical section taken on the line 3—3 of Fig. 1;

Fig. 4 is a horizontal section taken on the 55 line 4—4 of Fig. 1;

Fig. 5 is an enlarged plan view of the puncturing device and certain other parts found immediately below the line marked 5—5 of Fig. 1;

Fig. 6 is a transverse vertical section taken approximately on the line 6—6 of Fig. 5;

Fig. 7 is a detail section taken approximately on the line 7—7 of Fig. 5;

Fig. 8 is a transverse vertical section taken 65 on the line 8—8 of Fig. 5;

Fig. 9 is a view partly in side elevation and partly in vertical section taken on the line 9—9 of Fig. 8;

Fig. 10 is a fragmentary oblique section 70 taken approximately on the line 10—10 of Fig. 8;

Fig. 11 is a section taken on the line 11—11 of Fig. 1;

Fig. 12 is a perspective showing punches 75 and co-operating clamping bars removed from the punch-head;

Fig. 13 is a fragmentary perspective corresponding to Fig. 12, but showing a modified form of the punches;

Fig. 14 is a perspective showing a detached punch in modified form;

Fig. 15 is a detail in section illustrating a modified form of punch-head and punch clamping bars;

Fig. 16 is a fragmentary diagrammatic view showing punctures produced in the pole.

The pole Y is adapted to be placed upon a suitable truck and thereby delivered to 90 the puncturing machine. As shown, this pole carrying truck comprises the frame 17 having wheels 18 arranged to run on the rails 19 on the surface track. To support the pole free for easy rotation, the truck 95 frame 17 is provided with transversely spaced edgewise aligned pole supporting wheels 20, (see particularly Figs. 1 and 11).

Mounted in a pit, beyond one end of the track 19, is a bed frame 21, on the far end 100 of which, is supported a rigid skeleton main frame 22, preferably made from trussed commercial steel.

When delivering a pole to the puncturing machine, it will preferably be, nearly balanced on the supporting wheels 20 of the truck, but with the heaviest end of the pole presented to the machine. This relatively 105

- heavy end of the pole, when delivered to the machine, will be supported by peripherally toothed pole rotating and supporting wheels 23, best shown in Figs. 1 and 3. These 6 wheels 23 are secured to short shafts 24 journaled in the outer ends of arms 25, which arms, at their inner ends, are pivoted on a longitudinal shaft 26, journaled in suitable 10 bearings 27 on the bed frame 21. The arms 25, (see particularly Fig. 2) are bifurcated at their outer portions so that they embrace the toothed wheels 23 and are bifurcated at their inner ends so that their 15 bearings on the shaft 26 are interlapped.
- 16 The shaft 26 carries a spur gear 28 that meshes with spur gears 29 on the shafts 24 so that the two toothed wheels 23 will be simultaneously rotated at the same speed and in the same direction.
- 20 The toothed wheels 23 are made adjustable toward and from each other by oscillatory movement of the arms 25, and to adjustably support these arms, the outer ends 25 of the latter connected by links 30, (see 25 Figs. 2 and 3), to crank arms 31 secured to rock shafts 32 journaled in suitable bearings on the bed frame 21. These shafts 32, at their rear ends, are provided with worm 30 gears 33 that mesh with worms 34 on a cross-shaft 35 journaled in bearings 36 on the bed frame 21. Worm shaft 35, as shown, 35 is provided, at one end, with a bevel gear 37 that meshes with a bevel gear 38 on the lower end of an oblique operating shaft 39, which latter, as shown, extends through 40 a bearing on the main frame 22 and is provided with an operating wheel or hand-piece 40.
- 45 The gear 28 on shaft 26 meshes with a small pinion 41, journaled in suitable bearings on the bed frame 21 and provided with a worm gear 42. (See particularly Figs. 2 and 3.) Worm gear 42 is driven by a worm carried by a short transverse counter-shaft 44. Shaft 44 is journaled in bearings 45 on bed frame 21 with freedom for rotary and slight endwise movements, and at one end, said shaft is provided with a face friction wheel 46.
- 50 For driving this face friction wheel 46, a peripheral friction wheel 47 is keyed to slide upon, but to rotate with, a longitudinal driving shaft 48 journaled in suitable bearings 49 on the bed frame 21. (See Figs. 55 1, 2 and 3.) At its rear end, shaft 48 has a pulley 50 over which runs a belt 51. The upper portion of this belt, (see Figs. 1 and 4), runs over a pulley 52 carried by the extended armature shaft 53 of an electric motor 54, which latter is suitably mounted on an upper portion of the main frame 22. Armature shaft 53 also carries a spur pinion for a purpose which will presently appear, and its extended end is adapted to be connected 60 to an ordinary friction or cone clutch 56

to a punch driving shaft 57 journaled in the bearings 58, on the main frame 22. (See Figs. 1 and 4.)

The friction wheels 46 and 47 afford a variable speed transmission device and the shiftable peripheral friction wheel 47 is adapted to be set on the shaft 48 toward and from the axis of the wheel 46, for the transmission of different speeds, by the manipulation of a lever 59 pivoted to the bed frame 21 and connected to a shifting rod 60, the front end of which has a forked head 61 that engages the grooved hub of said wheel 47.

The face friction wheel 46 is adapted to be moved in or out of driving engagement with the peripheral friction wheel 47 by manipulation of a toggle 62—63. The toggle member 62 is pivoted to the bed frame 21 while the toggle member 63 is pivoted to the free end of a shifter lever 64. This shifter lever 64 is pivoted to a projection 21^a of the frame 21 and its intermediate portion is swiveled to the shaft 44, between collars 44^a of the latter. (See Figs 2 and 3.)

In the arrangement illustrated, the toggle member 62 has an extended end connected by a link 65 to the lever 66 that is pivoted to the bed frame 21, and the free end of this lever 66 is jointed to an upright lever 67, also pivoted to the bed frame 21 and located adjacent to the lever 59. (See particularly Fig. 1).

In Fig. 2, the toggle 62—63 is locked slightly past a dead center, thereby holding the face friction wheel 46 pressed into frictional driving engagement with the peripheral friction wheel 47; but when, by manipulation of lever 67, said toggle is buckled, the two friction wheels will be released from driving engagement so that they are thus caused to perform the additional functions of a clutch, or in-and-out of gear device.

For operating the clutch 56, a pivoted shipper lever 68 is connected to the movable clutch member and, as shown, is connected by links 69 to the upstanding arm 70 of a rock shaft 71 journaled in suitable bearings 72 on the top of the main frame 22. Rock shaft 71 has an arm 73, by means of which it may be operated to throw the clutch 56 into and out of action, at will. Said clutch will preferably be spring closed in the customary way, and to hold the same open, the links 69 and arm 70 may be arranged to move slightly beyond a dead center, as shown in Figs. 1 and 4.

The puncturing device is supported by the overhanging or projecting end of a cantilever beam 74 which, as preferably constructed, is in the form of a trussed horizontally disposed frame, the sides of which, at their rear ends, are pivotally connected to the main frame 22 by a transverse pivot

shaft 75, as best shown in Figs. 1 and 4. This beam 74 overlies and projects beyond the pole turning wheels 23. Said beam is adapted to be raised and lowered by suitable means, such as, a hydraulic cylinder and piston motor 76, the cylinder of which is anchored to the main frame 22, and the piston of which has an extended rod 77 attached to a cross-bar 78, the ends of which are pivoted to the side of the beam 74 by heavy shackle-bolts 79 or other suitable devices.

The hydraulic motor 76 may be operated by an ordinary rotary hydraulic pump 80, connected to the cylinder thereof by a pipe 81 in which is a three-way controlling valve 82 of well known construction.

The rotor of the hydraulic pump 80 is carried by the front end of a shaft 83, (see particularly Fig. 4), journaled in suitable bearings 85 on the frame 22 and provided, at its rear end, with a spur gear 86 that meshes with the pinion 55 on the armature shaft 53 of the motor 54. By the means just described, the free forwardly projecting end of the cantilever beam 74, and parts carried thereby, may be raised or lowered, at will.

Rigidly secured to the front ends of the sides of the beam 74 by means of angle brackets 87, is a transversely extended curved rail 88 and below this rail and extending rearward thereof, is a floating frame 89, shown as of rectangular angle steel structure. This frame 89, at the rear, has a rigidly secured bracket 90 to which is rigidly attached an upwardly projecting stem 91 that is swiveled in a head-block 92. The head-block 92 has projecting trunnions 93 by means of which it is pivoted for forward and rearward swinging movement in the flanges of angle brackets 94 rigidly secured to a cross-beam 95, which, in turn, is rigidly attached to the cantilever beam 74 by gusset plates 96. (See Figs. 5 and 6.) The stem 91 has a head 97 that limits its downward movement through the swinging block 92.

Near its front end, the floating frame 89 is hinged to short slotted links 98 that are loosely pivoted at 99 to traveling hanger brackets 100. These brackets 100 are bent to overlap the upstanding flange of the curved rail 88, and they are provided with wheels 101 and 102, the former of which run upon, and the latter of which run under the horizontal flange of the rail 88. Thus, the so-called floating frame 89 is hung from the beam 74 with freedom for vertical movement and for limited lateral traveling movements, all for an important purpose, which will hereinafter appear.

At its front and rear ends, the floating frame 89 is provided with depending, so-called, saddle-bars 103 that are curved in vertical plane, and as shown, are made up of laterally spaced flat metal straps having

intervening anti-friction rolls 104 for direct engagement with the upper surface of the log. (See particularly Fig. 6.)

The rear saddle-bar 103 is shown as pivotally secured to the rear bracket 90, while the front saddle-bar 103 is rigidly connected to a bracket 105, which, in turn, is rigidly secured to the front end of the floating frame 89.

The puncturing device which is carried directly by the floating frame 89, is made up of a plurality of independent units, located side by side, and capable of slight independent vertical movement to adapt themselves to the irregularities in the underlying surfaces of the pole. Each such unit, as shown, has its own independent cast casing 106 made up of a multiplicity of rigidly connected sections. These casings are independently pivoted on the shaft 107, (see particularly Figs. 5, 8, 9, and 10), journaled in the ends of the floating frame 89. The free or extended portions of the casings 106 are provided with stop lugs or projections 108 that are engageable with one side of the frame 89 to limit the downward movements of said casings, in respect to said frame. Working within the upper portion of these casings 106 and journaled thereto by trunnions 109, are crank disks 110 and 111 that carry a wrist pin 112. The so-called crank disk 110 is in the form of a gear that meshes with an intermediate gear 113 journaled within the casing. The gears 113 of the several units are driven by pinions 114 carried by the common shaft 107.

The wrist pins 112 are connected by crank rods 115 to punch-heads 116 that work freely within the lower portion of the respective casing 106. At their lower portions, the casings 106 are provided with rounded or reversely beveled pole-engaging surfaces 117 that are adapted to ride directly on the upper surface of the pole.

The punches that produce the punctures or indentations in the pole may take various different forms according to the extent of saturation desired or depending upon the nature of the wood of the pole to be punctured. The punches 118 shown in Fig. 12 are flat, dull edged, V-shaped steel elements formed with rectangular shanks 119 and upper end flanges 120. The shanks of these punches are arranged to be clamped between stiff clamping bars 121 and 122, detachably connected by machine screws 123. The punch-head, best shown in Figs. 8 and 9, at its lower end, is formed with a transverse seat into which the connected bars 121 and 122 with the applied punches 118, are adapted to be slid endwise, and the said bars are shown, as provided with lock flanges 124 to fit grooves in the punch-head 116. When a wedge strip 125 is driven into the seat of the head 116, as shown in Figs. 8 and 9, the

punch-equipped bar will be securely locked to the corresponding punch-head and the projecting ends of said bar will then be free to work vertically in slots 126. (See particularly Fig. 9.)

The construction illustrated in Fig. 13 is like that illustrated in Fig. 12, except that the punch points 118^a are formed with sharp points and sharp edges. The punch 118^b shown in Fig. 14 is a straight rectangular element having a dull, but slightly pointed end.

Fig. 15 shows the punches 118 clamped between dovetailed clamping bars 127 and 128 which fit a dove-tailed seat in the punch-head 116 and the numeral 129 indicates a wedge strip driven into said seat over the tops of the bars 127 and 128. With this arrangement, the driving of the wedge 129 forces the dove-tailed clamping bars 127 and 128 downward and tightly clamps the same against the punches 118.

Preferably, the punches 118 are alternately offset so that they produce a staggered row of punctures Y¹ in the pole Y, as, for example, illustrated in Fig. 16.

The punch driving shaft 107 is driven from the already noted shaft 57 through a jointed shaft 130 that is connected to said shafts 57 and 107, respectively, by universal joints 131 and 132. (See Figs. 1, 4 and 5.)

In Fig. 1, the numeral 133 indicates a liquid containing tank suitably supported from the main frame 22, and supplying liquid to the rotary pump 80 through a pipe 134.

The numeral 135 indicates a center pin suitably mounted on the main frame 22 and adapted to engage the adjacent end of the pole Y at its axis. This center pin is shown as provided with an offset scratch-all which, under rotation of the pole, will scratch or mark a circle on the end of the pole serving to indicate when the pole has been given one complete rotation.

Operation.

By manipulation of the hand wheel 40 and through connections already described, the toothed pole rotating wheels 23 may be raised, lowered, and properly spaced for the particular pole that is to be punctured. Then, when the said wheels 23 are driven, the pole will be rotated.

While the pole is being set into position on the wheels 23, the extended end of the beams 74 should be raised so as to lift the puncturing device clear of the pole. The beam 74 will be raised, as above stated, when liquid from the pump 80 is delivered to the cylinder 76, which operation has already been more fully described.

When the beam 74 is lowered, the puncturing device will be lowered until the roller-equipped saddle bars 103 rest upon the pole and the bearing surfaces 117 of the

independently movable casings 106 also rest upon the upper surfaces of the pole. The free end of the beam 74 should be lowered to such an extent that the floating frame 89 will be free to rise and fall slightly, thereby permitting the puncturing device to adapt itself to irregularities in the pole.

The puncturing device and the wheels 23 should be simultaneously operated, the former by closing the clutch 56 and the latter by engaging the face friction wheel 46 with the peripheral friction wheel 47. When the puncturing device is thrown into action, the several cranks 112 will be simultaneously rotated, the punch-head 116 will be vertically reciprocated and the punches 118 will produce the punctures Y¹ in the surface of the pole, while the latter is being rotated. One complete rotation of the pole, while the punches are in action, will produce the proper puncture in the pole. However, the number and closeness of the perforations made in the pole, for rotation thereof, may be varied by varying the speed of rotation.

The two roller-equipped saddle bars keep the puncturing units centered over the upper surface of the pole and, as one of said bars is pivoted, the two saddle bars will adapt themselves to all sorts of irregularities in the pole. Moreover, the wheels 101 may travel on the rail 88 and the floating frame 89 may move both laterally and vertically and the several puncturing units may independently move vertically, as already described, so that the puncturing devices are universally adjustable to all surface irregularities in the pole and the punches will be kept always operative centrally on the upper surface of the pole.

Of course, the joint shaft 130 permits the floating frame and the puncturing device to raise, lower, oscillate and move laterally, while properly transmitting the punch-driving power.

The above described machine or apparatus, while capable of large range of usage, is especially adapted for rapidly and economically puncturing long and heavy poles or logs, such as telegraph poles.

Broadly considered, the so-called casings 106 are head frames that independently support the punch heads for independent vertical movements.

What we claim is:—

1. In a machine of the kind described, means for supporting and rotating a pole, and a power-driven reciprocating puncturing device arranged to puncture the surface of the pole while it is being rotated.

2. In a machine of the kind described, means for supporting and rotating a pole, and a power-driven puncturing device arranged to puncture the surface of the pole while it is being rotated, said puncturing device comprising a plurality of adjacent units

capable of independent movement toward and from the pole to adapt themselves to irregularities in the pole.

3. The construction defined in claim 1 combined with power transmission mechanism whereby the speed of the puncturing device and pole rotating means may be varied, the one in respect to the other.

4. The combination with means for supporting and rotating a pole, of a beam overlying said pole, and a power-driven puncturing device suspended from said beam by connections permitting the same to drift or travel laterally during the puncturing operation.

5. The structure defined in claim 4 in which said puncturing device is provided with roller equipped saddles directly engageable with the pole.

6. The combination with means for supporting and rotating the pole, of a beam overlying the pole, a floating frame loosely supported from said beam, and a power-driven puncturing device mounted on said floating frame and operative on the pole while it is being rotated.

7. The structure defined in claim 6, in which said floating frame, at its ends, is provided with pole-engaging saddle bars.

8. The structure defined in claim 6, in

which said puncturing device comprises a plurality of puncturing units capable of limited independent vertical movement.

9. The structure defined in claim 6, in further combination with roller-equipped pole-engaging saddles on said floating frame, and means for raising and lowering said beam.

10. The structure defined in claim 6, in which said puncturing device comprises a common driving shaft, a plurality of head frames located side by side and independently pivoted on said driving shaft, cranks journaled on said head frames, and punch-equipped heads movable over said head frames and driven from the respective cranks.

11. The structure defined in claim 10, in which said floating frame has roller-equipped pole-engaging saddle-bars and said casings, in the vicinity of the punch-head, having pole-engaging surfaces.

12. The structure defined in claim 11, in which one of said saddle-bars is mounted for oscillatory movements in respect to the other.

In testimony whereof we affix our signatures.

JAMES E. LYNCH,
ARTHUR R. SANDT.
